ICE SKATE WALKER

Philip Gillett Cole, Tarrytown, N. Y.

Application April 30, 1934, Serial No. 723,114

6 Claims. (Cl. 208—183)

My present invention relates to an ice skate walker and constitutes an improvement over the device covered by United States Letters Patent No. 1,880,340, granted to me October 4, 1932.

As set forth in my aforementioned patent the device is intended for use in walking from a club house or hotel on ice skates to a skating pond located some distance away to prevent subjecting the skate blades to the dulling action which would result from repeated contact with the ground and for relieving the skater from ankle strain during such walking. More specifically, the objects of my present invention are to provide a device of the character set forth which will be of smaller size than those heretofore provided so as to be conveniently portable within the skater's skate shoes when not in use; which will provide a more efficient and effective holding engagement upon a skate blade; which will be of lighter weight and have compressible, anti-slipping means thereon to facilitate walking on skates, and to generally improve the device in its constructional details.

The invention will be better understood from the detailed description which follows, when considered in conjunction with the accompanying drawing which shows a preferred embodiment of my invention, and wherein

Figure 1 is a side elevation of my improved skate walker applied to an ice skate.

Fig. 2 is a top plan view of my ice skate walker.

Figs. 3 and 4 are end elevations taken from the right and left ends, respectively, of Fig. 2.

Figs. 5 and 6 are sections taken substantially along the planes of the lines 5—5 and 6—6 of Fig. 2.

Fig. 7 is a view similar to Fig. 6 showing the ice skate walker clamped to an ice skate blade.

Referring to the drawing, my ice skate walker may be said to comprise a sole or tread portion A which is formed on its upper side adjacent each end with upstanding lugs B and C flanking the longitudinal center line of the tread portion, with the lugs B on one side of said center line in somewhat spaced relation thereto, and the lugs C on the opposite side of said center line in more close relation thereto than the lugs B, and with the lugs on the same side of said center line in longitudinal alignment.

Supported and carried by the lugs B is a clamping member or bar D, the ends of which are turned back to provide substantially U-shaped portions d, the bight portion 2d at the toe end of the tread portion being seated and movable in a recess b

formed in the end of the lug B at said toe end, and the bight portion 3d at the heel end of said clamping member having a slot 4d therein through which extends a pin 2b which is secured in the outer end of the lug B at said heel end of the tread member. The recess b and the pin and slot connection 2b and 4d at the opposite ends of the clamping member serve to support said clamping member and guide it in its lateral movements toward and from the lugs C. Normally said clamping member is held in engagement with the inner face of the lugs B by a pair of leaf springs 3b, one end of which is secured to said clamping member and the other end of which bears against the outer faces of the lugs B.

For moving the clamping member D inwardly toward the lugs C for clamping engagement with a skate blade E, the tread portion on its upper side approximately midway between the heel and toe portions thereof is provided with upstanding lug F upon which is pivotally mounted a cam G having an operating handle g. The pivotal connection for the cam G is provided by a rivet 2g having an enlarged shank 3g, the head of which engages over the top face of the cam and the opposite end of which bears upon the upper side of the tread portion, while the end of the rivet shank is peened over or upset against a bearing surface on the underside of the tread portion. Preferably the lug F is formed to provide a substantial bearing surface for the face of the cam, as will be apparent from an inspection of the drawing. The pivotal mounting for the cam G is such that when the operating handle g is in its full line position, as shown at Fig. 2, the cam is inoperative; and as said handle is moved around its pivot in a clockwise direction the cam engages the clamping member D and moves it inwardly toward the lugs C, the limit of said movement being reached when the operating handle is moved through an arc of approximately 180°.

To promote the gripping and holding action of the clamping member upon the skate blade E, the lugs C are each provided with a U-shaped jaw or clip H which is pivotally mounted upon said lug by a pin h which extends through the arms of the clips and longitudinally through the lugs. Normally the bight of the U-shaped clips or the engaging faces thereof are caused to assume a position inclined to the upper face of the tread portion and extending upwardly and outwardly from the center line thereof by being acted upon by a bullet nose pawl J which is urged inwardly by a spring i, the said spring-pressed pawl being mounted in a cup-shaped member K which is 55

force-fitted or otherwise held within a recess *c* in the lug. For further insuring the holding of the device upon racing skate blades, which are usually provided with a longitudinally-extending rib disposed in substantial parallel relation to the skating edge on either face of said blade, I provide the blade-engaging faces of the clamping member and the clips with complementary grooves *4b* and *2c*, respectively. To avoid the entire clamping member engaging the skate blade when in clamping relation thereto, said clamping member may have the portion thereof *5d* which is intermediate the clamping ends thereof, bent inwardly, as best shown in Fig. 2.

It will be obvious that the skate walker can be made of any suitable material, preferably aluminum or an aluminum alloy, so as to reduce its weight to a minimum, and that it may also have its net weight further reduced by being formed of a width of material to provide a tread outline which may be reinforced by one or more transversely-extending connecting ribs such as *2a*. To promote ease in walking on skates with the aid of my skate walker, I find it preferable to give to said sole or tread member a slightly curved or arched contour in a longitudinal direction, as best shown in Fig. 1, and to further ease said walking and prevent slipping in walking upon ice, I prefer to provide the underside of said tread portion with spaced, compressible, anti-slipping means or calks *L*. These calks may be made of any preferred form and material, such, for example, of a rubber composition in semi-spherical form provided with a metallic pin *l*, the head of which is vulcanized into said rubber, which calks may be mounted in shallow recesses *3a* having central pin openings therein formed in the underside of said tread portion. In practice it may be advisable to cement said calks within said recesses in addition to driving the pins *l* into the pin openings provided therefor.

In practice, the skate walker as disclosed, may be used on either a right or left shoe, or, if desired, it may be made with the cam-operating means on opposite sides so as to be more readily adapted for right and left shoes. In the application of my skate walker to a skate blade it is merely necessary to position the blade of the skate between the clamping member and the jaws or clips on the lugs *C* and move the operating handle *g* through an arc of approximately 180° to move the clamping member into clamping position. The removal of the device from the skate can be readily accomplished by merely moving the handle in the opposite direction, whereupon the springs *3b* will function to move the clamping member out of clamping position. In the clamping operation it will be appreciated that the clamping faces of the clips *H* are moved from their normally outwardly-inclined position into either substantially parallel or somewhat inclined or clamping relation with the ice skate blade, and when in said position the springs *j* contribute in clamping the device upon the skate blade.

From the foregoing detailed description it will be apparent that I have provided a simple, efficient and novel form of ice skate walker, and while I have shown and described but a single embodiment of device I do not wish to be limited to the precise details of construction disclosed

therein since modifications thereof may be resorted to without departing from the spirit of the invention.

What I claim is:

1. A skate walker or the like, comprising a sole or tread portion having on its upper side movable clamping means and an abutment between which the blade of an ice skate can be clamped, and resilient means normally urging the skate blade engaging face of the abutment toward the clamp- 10 ing means. 5

2. A skate walker or the like, comprising a sole or tread portion having on its upper side movable clamping means and an abutment between which the blade of an ice skate can be clamped, said abutment having a pivotally mounted spring-pressed skate blade engaging face. 15

3. A skate walker or the like, comprising a sole or tread portion having on its upper side cam operable clamping means and an abutment between 20 which the blade of an ice skate can be clamped, said abutment having a spring-pressed skate blade engaging face. 20

4. A skate walker or the like, comprising a sole or tread portion having on its upper side movable clamping means and an abutment between which the blade of an ice skate can be clamped, said clamping means having portions thereof disposed in a plane substantially parallel to the face of the blade to be engaged thereby and movable laterally relatively to the abutment, and said abutment having a skate blade engaging face which is normally disposed at an angle to the face of the blade to be engaged thereby and adapted to be moved into facial engagement with said blade as 30 the blade is moved thereagainst by the clamping means. 30

5. A skate walker or the like comprising a sole or tread portion having on its upper side an abutment adjacent the heel and the toe portions 40 thereof on one side of the longitudinal center line thereof and in proximity thereto, and clamping means on the other side of said center line in proximity thereto, and between which abutments and clamping means an ice skate blade can be 45 clamped, said clamping means having portions thereof disposed in a plane substantially parallel to the face of the blade to be engaged thereby and movable laterally relatively to the abutments, and said abutments having skate blade engaging faces 50 which are normally disposed at an angle to the face of the blade to be engaged thereby and adapted to be moved into facial engagement with said blade as the blade is moved thereagainst by the clamping means. 55

6. A skate walker or the like, comprising a sole or tread portion having on its upper side adjacent each end two upstanding lugs flanking the longitudinal center line of the tread portion with the lugs on the same sides of said center line being in longitudinal alignment, a movable clamping member supported and guided by the lugs on one side of said center line and normally held away from said center line by resilient means and manually operable means for moving said clamping member laterally toward the lugs on the opposite side of said center line to clamp an ice skate blade between said last mentioned lugs and said clamping member. 60
